179,966

RANGE

Russell R. Dunbar, Detroit, Mich., assignor to General Motors Corporation, Detroit, Mich., a corporation of Delaware

Application October 8, 1956, Serial No. 43,262

Term of patent 7 years

(Cl. D81—4)

Fig. 1

Figure 1 is a perspective view showing the front, top and one side of a range, embodying my new design, the opposite side of the range being identical with the side shown; and

The dominant features of my design reside in the portions shown in full lines.

I claim:

The ornamental design for a range, as shown and described.
